UNITED STATES PATENT OFFICE

138,142

DESIGN FOR A NOSE AND THROAT TREATMENT CABINET

Aaron A. Goldstein, Buffalo, N. Y., assignor to
The Gomco Surgical Manufacturing Cor-
poration, Buffalo, N. Y., a corporation of New
York

Application October 9, 1943, Serial No. 111,323

Term of patent 14 years

(Cl. D83—1)

To all whom it may concern:

Be it known that I, Aaron A. Goldstein, a citizen of the United States, residing at Buffalo, in the county of Erie and State of New York, have invented a new, original, and ornamental Design for a Nose and Throat Treatment Cabinet, of which the following is a specification, reference being has to the accompanying drawings, forming part thereof.

In these drawings:

Fig. 1 is a perspective view of a nose and throat treatment cabinet embodying my new design and showing the same closed.

Fig. 2 is a similar view showing the compartment lid and side door open.

That end of the cabinet which is not shown is substantially similar to the end shown in Fig. 1. The characterizing features of the design reside in the cabinet disclosed, having the configuration, proportions and arrangements of parts specifically as shown.

I claim:

The ornamental design for a nose and throat treatment cabinet, as shown and described.

AARON A. GOLDSTEIN.
